UNITED STATES PATENT OFFICE.

SWANTE J. P. SWALLENDER, OF CHICAGO, ILLINOIS, ASSIGNOR OF ONE-HALF TO WILL M. UPDEGROVE, OF CHICAGO, ILLINOIS.

CLOTHES-PRESSING MACHINE.

1,294,567.

Specification of Letters Patent. Patented Feb. 18, 1919.

Application filed March 18, 1918. Serial No. 222,998.

To all whom it may concern:

Be it known that I, SWANTE J. P. SWALLENDER, a citizen of the United States of America, and a resident of Chicago, in the county of Cook, State of Illinois, have invented certain new and useful Improvements in Clothes-Pressing Machines, of which the following is a specification.

This invention relates to that type of clothes pressing machine in which a stationary lower buck or platen supports the goods to be pressed, and a movable press head exerts the required pressure through an overhead transverse lever carrying said press head at a forward end and connected at the rear end with the power mechanism, and the present improvement has for its object:

To provide a simple and efficient structural formation and association of parts whereby the pressing movement of the movable press head or platen of a clothes pressing machine is attained in an efficient, economical and convenient manner, all as will hereinafter more fully appear.

25 Figure 1, is an end elevation of an ordinary type of clothes pressing machine having the present improvement applied.

Fig. 2, is a detail front elevation of the operating treadle and accessories of the controlling valve of the machine.

Like reference numerals indicate like parts in both views.

Referring to the drawing, 1 designates the stationary platen or "buck" mounted in a raised position above the supporting stand 2 of the machine, and 3 designates the movable platen or press head carried on the end of an overhead transverse lever 4 pivoted near its mid-length to the upper end of a post or standard 5 forming a part of the supporting stand 2 aforesaid.

6 designates a pin or stud carried on the rear end of the lever 4 aforesaid, for operative engagement with the hereinafter described push bar forming a part of the power means of the machine.

7 designates a power cylinder mounted in a rearwardly inclined position on a similarly inclined supporting bracket 8 fixedly attached to the rear portion of the supporting stand 2 aforesaid, and having a piston and piston rod 9, the upper end of which has pivotal connection with the push bar above referred to, and as shown in Fig. 1.

55 10 designates the push bar above referred to, and which is pivotally connected at its

lower end to the piston rod 9 aforesaid, and formed near its upper end with a hook shape shoulder 11 adapted for engagement beneath the pin or stud 6 aforesaid, so that when steam or like pressure is admitted into the lower end of the power cylinder 7, a powerful upward movement of said inter-engaged parts will take place, to in turn impart a like powerful downward movement 65 to press head 3 and upon the garment or other article supported on the buck 1.

The purpose of the above described detachable connection between the push bar 10 and the rocking frame 4, is to permit of 70 an extended rocking movement of said frame, by hand, and which is found convenient and necessary in the attainment of the various operations of the machine in placing and replacing the goods or articles 75 operated on. The short and powerful final downward movement of the press head 3 is attained by the power cylinder 7, which in the present structure has a comparatively short stroke, with a corresponding economy 80 in the amount of steam required to operate the same.

12 designates a bell-crank lever fulcrumed to the pedestal of the platen or buck 1 and having link connection 13 with the aforesaid 85 push bar 10 for effecting a convenient disengagement of said push bar from its operative engagement with the rocking frame 4, when it is desired to effect by hand the above mentioned greater range of movement of 90 said rocker frame 4 and associated press head 3.

14 designates a spring by which the link connection 13 is connected with the post or standard 5 and tending to move the push 95 bar 10 to its operative engagement with the rocking frame 4 aforesaid.

15 designates a controlling valve, usually of the ordinary three-way type, and having a pipe connection 17 with a source of steam 100 pressure supply, with a pipe connection 16 to an exhaust steam receiver, and with a pipe connection 18 to the power cylinder 7 aforesaid.

19 designates a rock lever attached to the 105 movable member or plug of the controlling valve 15 aforesaid, with its respective ends formed with stirrup recesses for convenient operation by the foot of the operator, to effect the three-fold operations of admitting 110 steam to the power cylinder 7, permitting an exhaust of steam from said cylinder, and

for shutting off the supply of steam to said cylinder.

Having thus fully described my said invention, what I claim as new and desire to secure by Letters Patent, is:—

A clothes pressing machine comprising a supporting frame having a standard, a supporting bracket at the rear portion of the supporting frame, a platen or buck having a pedestal and mounted on the supporting frame, a lever pivoted to the standard having a press-head at its forward end, a stud at its rear end, a power cylinder mounted on the bracket having a piston and rod,

a push bar having a shoulder at its upper end, on which the stud is adapted to seat, and pivoted at its lower end to the piston rod, a bell-crank-lever fulcrumed to the pedestal, a link connection between the push-bar and the bell-crank-lever, a spring connecting the standard with the link connection, a fluid supply pipe connected with the power cylinder and a controlling valve for the fluid supply pipe.

Signed at Chicago, Illinois, this 16th day 20
of March 1918.

SWANTE J. P. SWALLENDER.
